UNITED STATES PATENT OFFICE.

EDWIN F. BEUGLER, OF BUFFALO, NEW YORK, ASSIGNOR TO E. & B. HOLMES MACHINERY COMPANY, OF BUFFALO, NEW YORK, A CORPORATION OF NEW YORK.

HEADING-PRESS.

1,111,559.

Specification of Letters Patent. Patented Sept. 22, 1914.

Application filed April 24, 1913. Serial No. 763,264.

To all whom it may concern:

Be it known that I, EDWIN F. BEUGLER, a citizen of the United States, residing at Buffalo, in the county of Erie and State of New York, have invented new and useful Improvements in Heading-Presses, of which the following is a specification.

This invention relates to a machine which is designed to press together the several sections or pieces of wood which are united by means of dowel pins for the purpose of producing heading from which circular barrel heads are cut. In order to produce a tight joint between the butting edges of the heading section strips of flagging or similar material are usually placed in these joints.

It is the object of this invention to provide a machine of comparatively simple and durable construction whereby the operations of pressing the sections together over opposite ends of dowels and pointing of the dowels for facilitating placing the flagging between the heading sections is effected expeditiously, conveniently and economically.

In the accompanying drawings: Figure 1 is a vertical longitudinal section of a heading press embodying my improvements. Fig. 2 is a top plan view thereof. Fig. 3 is a rear end elevation thereof. Fig. 4 is a front end elevation of the same. Fig. 5 is a vertical transverse section taken in line 5-5, Fig. 1. Fig. 6 is a vertical transverse section, on an enlarged scale, taken in line 6-6, Fig. 7 and showing the cutter mechanism whereby the front ends of the dowel pins are pointed. Figs. 7 and 8 are vertical sections taken in the correspondingly numbered lines in Fig. 6.

Similar characters of reference indicate corresponding parts throughout the several views.

1 represents the main frame of the machine which may be of any suitable construction to support the various working parts of the machine. On its upper part this frame is provided with a horizontal longitudinal table 2 upon which is supported the sections 3 of the barrel heading in a horizontal crosswise position while the opposing edges of two adjacent heading sec-

tions are pressed toward each other and upon opposite ends of dowel pins 4 which are adapted to connect the heading sections. In practice the holes 5 in the edges of the heading sections are bored therein at the proper places by a separate machine before the heading is assembled in the press. In the case of heading composed of more than two sections, as shown in Fig. 1, each intermediate section is provided with openings in its opposite edges while the end sections are only bored on their inner edges. The front end of each dowel is pointed or sharpened, as shown at 6, so as to permit of readily slipping a piece of flagging 7 over the same to produce a tight joint between adjacent heading sections. For convenience in assembling the heading sections, dowel pins and flagging, two receptacles or boxes 8, 9 are mounted by means of a bracket 100 on the adjacent upper part of the frame and adapted to contain a supply of pins and flagging respectively.

Upon the front part of the table is mounted an anvil 10 which extends transversely across the same and rests with its back against a shoulder or abutment 11 formed on the adjacent part of the main frame. This anvil is detachably secured to the frame by means which preferably consists of two hook bolts 12 extending vertically through openings in the front part of the frame and engaging the hooks at their upper ends with the top of the anvil while their lower ends are provided with screw nuts 13 which engage with the underside of the frame and operate when tightened to press the anvil against the upper side of the table. Arranged horizontally in the anvil and lengthwise of the machine are a plurality of sockets or openings 14, preferably two in number each of which is adapted to receive the front end of one of the dowel pins whereby the opposing edges of two heading sections are connected. When placed in this socket the dowel pin is square at its opposite ends and rests with its square or straight front end against the flat or vertical bottom or stop face 15 of the socket. While in this position the dowel pin is firmly supported

so as to permit a heading section which is placed with the openings in its front edge in engagement with the rear ends of the dowel pins to be effectively pressed or driven forwardly until this heading section bears against the face of the anvil and the dowel pins are driven the proper distance at their rear ends into the openings of the respective heading section. This driving of a heading section upon the dowel pins and against the anvil is effected by means which comprise a ram or hammer 16 which is adapted to engage with the rear edge of the heading section. This hammer or ram is mounted to slide horizontally and lengthwise back and forth on the upper rear part of the frame or table, the connection between this hammer and the table being preferably so constructed that the hammer or ram is free to slide lengthwise on the frame but is incapable of vertical movement thereon. As shown in Figs. 3 and 5 this is accomplished by means of two laterally projecting guide flanges 17 arranged horizontally and lengthwise on the upper part of the frame and engaging with longitudinal glide grooves 18 formed on the inner sides of two guide flanges 19 depending lengthwise from opposite longitudinal edges of the hammer and along opposite sides of the table.

In the operation of assembling a plurality of heading sections for the purpose of producing a complete heading which is ready to be cut into circular form to fit a barrel the operator first places a set of dowel pins in the sockets of the anvil, then places the first section of the heading upon the table with its openings in line with the dowel pins and then causes the hammer or ram to be moved forwardly so as to deliver a blow against the rear edge of the respective heading section and force the same with its openings upon the dowel pins after which the hammer is again retracted into its rearmost position.

Preparatory to moving the respective heading section rearwardly together with the dowel pins into position for assembling the next heading section therewith the front ends of the dowel pins are pointed or cut off on a bevel while these pins are still within the sockets of the anvil and engaging their straight front ends with the vertical stop face thereof. Various means may be employed for this purpose but those shown in the drawings are suitable and preferred and constructed as follows: 20 represents a cutter blade which reciprocates horizontally and transversely in a guideway which intersects the front ends or inner parts of the sockets which receive the dowel pins, this guideway being formed by the bottom of a horizontal transverse groove 21 in the upper side of the anvil engaging with the under-

side of the blade and two retaining blocks 65 22, 23 secured in the upper part of this groove by means of screws 24 so as to engage the upper side of the blade. The latter and its guideway are inclined in a direction lengthwise of the machine or transversely 70 of the blade and the same is provided with a cutting edge 25 at its front end which is adapted to pass back and forth past one of the dowel pin sockets and another cutting edge 26 which is arranged on the rear edge 75 of a notch 240 in the lower edge of the blade and adapted to pass back and forth across the other dowel pin socket. In the retracted position of this cutter blade its cutting edges clear the dowel pin sockets, as shown in Fig. 80 6, and while in this position the dowel pins rest squarely at their inner ends against the stop face of the anvil and receive a longitudinal thrust while the heading section is driven on to the same. After the heading 85 section and the dowel pins have been thus assembled the cutter blade is moved forwardly so that its cutting edges move across the front ends of the dowel pins and sever the same on a bevel, whereby the dowel pins are sharpened or pointed for convenience in subsequently threading or slipping a piece of flagging over the same. The reciprocating movement of the dowel pin cutter may be effected by various means, for 95 instance by the means which are shown in Figs. 1, 2, 3 and 4 of the drawings and which comprise a vertically swinging elbow lever 27 pivoted on the right hand side of the main frame, a fork 28 secured to the 100 right hand end of the cutter blade and embracing the upper arm of the elbow lever, a vertically swinging treadle 29 arranged lengthwise in the lower front part of the frame and having its rear end pivoted by means of a transverse pin 30 on the lower part of the frame, a link 31 connecting the treadle with the lower arm of the elbow lever, and a spring 32 connecting the treadle with the adjacent part of the main frame 110 and operating constantly to raise the treadle and to turn the elbow lever so as to move the cutter into its inoperative position toward the right of the machine.

When the operator desires to point a set 115 of dowel pins which are arranged within the anvil he depresses the treadle whereby the cutter is moved forwardly across the dowel pins and cuts them off on a bevel and immediately thereafter removes the pressure 120 of the foot from the treadle permitting the spring 32 to again retract the cutter into its inoperative position preparatory to pointing the next set of dowel pins.

After the front ends of a set of dowel pins 125 have been thus pointed the same and the heading section attached thereto are moved inwardly so that the dowel pins which have

been just sharpened are exposed in rear of the face of the anvil. The operator now takes a strip of flagging and impales the same on the dowel pins which operation is facilitated by the pointed ends of the dowels piercing holes freely in the flagging. After placing another set of unpointed dowel pins in the sockets of the anvil and another section of the heading between the rear ends 5 of the pins in the anvil and the front ends of the pins on the previous heading section so that the corresponding dowel pins and dowel openings of the heading sections are in alinement the operator again causes the 10 ram or hammer to advance and strike a forward blow against the rear heading section, whereby the latter is driven forwardly until it engages its front edge with the rear edge of the front section and its dowel pins enter 15 the rear openings of the front section and the openings in the front edge of the front section are driven upon the rear ends of the dowel pins in the anvil. During this operation the opposing edges of the two heading 20 sections are tightly pressed together against opposite sides of the flagging between them. If the barrel for which the heading is intended does not require a perfectly tight joint between the heading sections or if the 25 opposing edges of the heading sections have been previously planed sufficiently accurate 30 to produce a tight joint between the same without the use of flagging the latter may be omitted in which case the heading sections 35 bear directly against each other at their opposing edges. After thus assembling the second heading section with the previous section and applying the last mentioned set of dowel pins thereto the operations 40 of first sharpening the last set of dowel pins, then moving the same rearwardly with the heading sections, applying a strip of flagging to the last set of dowel pins and assembling the same with the next 45 following heading section are repeated in the same manner as has been described with reference to the other heading sections. As many heading sections as required may be thus connected by means of dowel pins in 50 this manner as the width of heading sections or the size of barrel for which the heading is intended may require, it being understood that the outer edges of the first and last heading sections are not provided with 55 dowel pin openings inasmuch as they do not require the same.

In the drawings the anvil is provided with two dowel pin sockets for the purpose of connecting adjacent heading sections by 60 means of two dowel pins but if desired a different number of dowel pin sockets may be employed if the character of the heading which is built up makes this desirable. In building up heading for different sizes of 65 barrels the distance between the dowel pins

and the size of the dowel pins varies to suit the particular size of heading and in order to enable this machine to be used for making up heading of different sizes a number of anvils are preferably made up each of 70 which is designed to receive the pins of a certain size and spaced apart a distance to suit a particular barrel heading. It is therefore possible to interchange the anvils one for another in the machine and quickly 75 adapt the same for various sizes of heading.

The outer longitudinal edges of the end sections of the heading are usually not planed or trimmed and therefore seldom parallel with the joints between the several heading sections. In order therefore to permit the hammer to engage the rear edge of the rear heading section so as to properly press the same together the striking face 33 at the front end of the hammer is curved horizontally of convex form which permits the same to adapt itself to any variation in the form of the rear edge of the rear heading section and press the several sections together properly. The rear end of the hammer is provided with a similar horizontally and transversely curved convex face 34 which may be substituted for the front face 33 when the latter becomes worn by simply reversing the hammer end for end on the 85 table.

The preferred means for reciprocating the ram or hammer which are shown in the drawings are constructed as follows: 35 represents an upright hammer rock lever 100 which swings in a vertical plane lengthwise of the machine and has its central part moving through a longitudinal slot 36 formed in the upper part of the main frame while its upper free end is operatively connected with the ram or hammer and its lower end is pivoted on the lower part of the main frame, preferably by the same pin 30 by which the rear end of the treadle is pivotally connected with the frame, as shown 105 in Figs. 1 and 5. Various means may be employed for adjustably connecting the upper end of the hammer lever for the purpose of adapting the position of the hammer to suit the particular width of the completed heading which is to be produced by the machine. The means shown in the drawings for this purpose comprise a longitudinal slot 37 formed lengthwise in the hammer and receiving the upper part of the hammer lever, and an adjustable bearing block 38 secured to the upper side of the hammer so as to be capable of longitudinal adjustment thereon and provided with an opening 39 which receives the upper end of 110 the hammer lever. The means shown in the drawings for adjustably connecting the bearing block with the hammer preferably comprise two clamping bolts 40 passing through the bearing block on opposite sides of the 115

hammer lever and through longitudinal slots 41 in the hammer on opposite sides of its central slot which receives the hammer lever. Upon loosening these bolts 40 the hammer may be shifted lengthwise of the table and then secured to the bearing block by tightening the bolts 40, thereby enabling the hammer to be adjusted into position for operating upon different sizes of barrel heading. In order to relieve the clamping bolts 40 from undue strain and preventing the same from becoming loose by the constant blows which are delivered by the hammer against the heading the bearing block 15 and the hammer are positively interlocked in the various positions to which the same may be adjusted by means of transverse ribs 42 or other projections formed on the under-side of the bearing block and engaging with 20 one or the other of a plurality of transverse notches, recesses or grooves 43 formed in the upper side of the hammer.

The backward movement of the hammer lever together with the hammer operatively connected therewith is effected by spring pressure. The device for this purpose which is shown in the drawings preferably comprises two return springs 44 arranged horizontally one above the other lengthwise in 30 the lower part of the machine, a front yoke 45 connecting at its opposite ends with the front ends of these two springs, a clevis 46 connecting the central part of this front yoke with the lower part of the hammer 35 lever, a rear yoke 47 having its opposite ends connected with the rear ends of the return springs, an adjustable supporting or tension arm 48 engaging with the inner side of the rear yoke, an adjusting screw 49 connected with the adjusting arm and working 40 in a threaded opening in the rear lower part of the main frame, and a clamping nut 50 applied to the adjusting screw and bearing against the rear end of the frame, as best 45 shown in Figs. 1, 2 and 3. Upon turning the adjusting screw together with its arm so as to move the same backwardly or forwardly the tension of the return springs 44 may be regulated as desired and after adjustment 50 the tension or adjusting arm is held in position by means of the clamping nut 50.

The forward movement of the hammer lever together with the hammer for delivering a blow against the heading is effected 55 by means of a pair of upper and lower friction rollers 51, 52 which are adapted to operatively engage with the upper and lower sides of a horizontally and longitudinally movable friction beam 53 which is operatively connected with the central part of the hammer lever. As shown in Figs. 1 and 5, the connection between the friction beam and the hammer lever is preferably produced by a coupling or pivot block 54 which 60 is secured at its rear end by a bolt 57 or

otherwise to the front end of the friction beam and provided with an opening 56 through which the central part of the hammer lever passes, and a pivot pin 55 passing horizontally and transversely through the pivot block and the hammer lever. One of these friction rollers preferably the upper one 51 is mounted on a transverse shaft 58 which is journaled in fixed bearings 59 on the main frame and is rotated continuously 70 in the direction of the arrow shown in Fig. 5 by means of a driving belt passing around a pulley 60 mounted on one end of the shaft 58. The other or lower friction roller 52 is mounted on a shaft 61 journaled in vertically movable bearings 62 which are preferably formed on an L-shaped yoke having a horizontal arm 63 projecting rearwardly from the axis of the roller and pivoted by means of a transverse pin 64 on the adjacent part of the main frame so that the yoke swings vertically. The lower friction roller is yieldingly held in its lowered position by means of a spring 65 connected at one end with the lower arm 66 of the elbow-shaped 80 yoke and at its other end with an adjusting screw 67 mounted on the adjacent part of the main frame. The two friction rollers are caused to turn together by intermeshing gear wheels 80, 81 secured to the shafts 58 85 and 61, respectively.

Normally the friction rollers do not engage operatively with the friction beam so that the latter together with the hammer connected therewith is held in its rearmost 90 position by means of the return springs 44. When it is desired to deliver a blow of the hammer against the heading the yoke supporting the lower driving roller is raised sufficiently to cause the friction beam to be gripped between the upper and lower friction rollers whereby the friction beam is moved forwardly quickly by the power driven upper friction roller and the hammer is caused to move forwardly and deliver a blow against the heading after which the lower friction roller is again lowered to permit the return springs to move the hammer into its backward position. This raising of the lower friction roller is preferably effected by means of a hand lever pivoted to swing vertically on the lower central part of the main frame by means of the transverse pin 68 and having a rear single arm 69 engaging with an adjusting screw 100 105 70 on the lower part of the friction roller yoke and provided with two front arms or handles 71 which project forwardly and lengthwise along opposite sides of the main frame within convenient reach of the operator while the same is standing at the front end of the machine. These handles are preferably guided in loops 72 on opposite sides of the main frame so as to prevent lateral displacement of the same. 110 115 120 125 130

Upon depressing the front arms of the hand lever the rear arm thereof lifts the lower friction wheel or roller for causing the hammer to be moved forward quickly and drive the heading over the pins and against the anvil and upon releasing this hand lever the front arms thereof are raised and the lower friction wheel or roller is depressed by the spring 65 thereby releasing the grip of the friction wheels on the friction beam and permitting the return springs 44 to retract the hammer.

By employing two front arms on the hand lever which controls the friction operating mechanism of the hammer it is possible for the operator to cause the hammer to advance by the use of either one hand or the other. By instructing the operator to always use both hands on the two front arms for operating the friction driving mechanism of the hammer the danger of catching the fingers of the operator between the sections of the heading and possibly injuring the same is avoided.

In order to avoid undue jarring of the machine at the end of the forward and backward stroke of the hammer a cushion device is provided which preferably comprises front and rear springs 73, 74 which are arranged in pockets 75, 76 at the front and rear ends of the slot 36 in position to be engaged by the front and rear sides of the hammer lever at the front and rear ends of the stroke of the same.

My improved heading press is very compact in construction, the same can be very conveniently and expeditiously operated and the same can be very readily adapted for producing heading at comparatively low cost for barrels of different sizes.

I claim as my invention:

1. A heading press comprising a table adapted to support the heading, an anvil arranged on the table and provided with sockets adapted to receive dowel pins, and with abutting faces arranged at right angles to said pins for engaging the rear ends of the latter, and a hammer movable toward and from said anvil.

2. A heading press comprising a table adapted to support the heading, an anvil arranged on the table and provided with sockets adapted to receive dowel pins, and with abutting faces arranged at right angles to said pins for engaging the rear ends of the latter, a hammer movable toward and from said anvil, and means for pointing the ends of said dowel pins while engaging said abutment.

3. A heading press comprising a table adapted to support the heading, an anvil arranged on the table and provided with sockets adapted to receive dowel pins, and with abutting faces arranged at right an-

gles to said pins for engaging the rear ends 65 of the latter, a hammer movable toward and from said anvil, and means for pointing the ends of said dowel pins while engaging said abutment comprising a cutter blade movable at an angle across the inner ends of 70 said sockets.

4. A heading press comprising a table adapted to support the heading, an anvil mounted on the table and provided with 75 sockets for receiving dowel pins and having a guideway extending across said sockets and formed by the bottom of a groove in the anvil and a retaining block secured in the upper part of said groove, and a cutter 80 blade sliding in said guideway and adapted to point the front ends of the dowel pins in said sockets.

5. A heading press comprising a table adapted to support the heading, an anvil mounted on the table and provided with 85 sockets for receiving dowel pins and having a guideway extending across said sockets and formed by the bottom of a groove in the anvil and a retaining block secured in the upper part of said groove, a cutter 90 blade sliding in said guideway and adapted to point the front ends of the dowel pins in said sockets, and means for reciprocating said cutter blade in said guideway.

6. A heading press comprising a table 95 adapted to support the heading, an anvil mounted on the table and provided with sockets for receiving dowel pins and having a guideway extending across said sockets and formed by the bottom of a groove 100 in the anvil and a retaining block secured in the upper part of said groove, a cutter blade sliding in said guideway and adapted to point the front ends of the dowel pins in said sockets, and means for reciprocating 105 said cutter blade in said guideway, comprising an elbow lever having one of its arms connected with said cutter blade, a treadle connected with said elbow lever, and a spring for retracting said treadle and the 110 parts associated therewith.

7. A heading press comprising a table adapted to support the heading and provided with an abutment, an anvil removably engaging with said abutment and provided 115 with sockets adapted to receive dowel pins, and means for securing said anvil to the table comprising a clamping bolt mounted on the table and having a hook engaging with the upper side of said anvil.

8. A heading press comprising a frame having a table adapted to support the heading on its underside, an anvil arranged at one end of the table and adapted to support the heading at one edge thereof, a movable hammer adapted to strike the opposite edge of the heading and means for moving the hammer toward and from the anvil com-

rising a rock lever pivoted on the frame and means for adjustably connecting the hammer with said lever comprising a bearing block resting on the hammer and provided with an opening which receives said lever, and bolts arranged in said block and in longitudinal slots in said hammer.

Witness my hand this 22nd day of April, 1913.

EDWIN F. BEUGLER.
